(57) **CLAIM**

The ornamental design for a tracking roller, as shown and described.

DESCRIPTION

FIG. 1 is a front, top perspective view of a tracking roller showing my new design;

FIG. 2 is a front elevational view thereof;

FIG. 3 is a side elevational view thereof;

FIG. 4 is a rear elevational view thereof;

FIG. 5 is a side elevational view of the other side thereof;

FIG. 6 is a top plan view thereof; and,

FIG. 7 is a bottom plan view thereof.

The broken line showing of the holes on the tracking roller is for illustrative purposes only and forms no part of the claimed design.
